UNITED STATES PATENT OFFICE.

SAMUEL H. DUNNING, OF PATERSON, NEW JERSEY.

STOP-COCK FOR AIR-BRAKE SYSTEMS.

No. 838,308.

Specification of Letters Patent.

Patented Dec. 11, 1906.

Application filed April 7, 1906. Serial No 310,514.

To all whom it may concern:

Be it known that I, SAMUEL H. DUNNING, a citizen of the United States, residing in Paterson, county of Passaic, State of New Jersey, have invented certain new and useful Improvements in Stop-Cocks for Air-Brake Systems; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention is an improvement in stop-cocks for the main air-pipes of air-brake systems.

It has for its object to so construct a stop-cock of this nature and used for substantially 20 the purpose indicated that the same may not be tampered with by unauthorized persons, so as to cut off any part of the system, at least without the engineer or other person in control of the system being advised thereof.

25 To this end my invention consists in a stop-cock provided with means controlled by a key for locking the valve thereof in the open position, and, furthermore, so constructed that even though the valve be surreptitiously 30 unlocked and then closed the system will be automatically vented so as to set the brakes on all the cars corresponding to the part of the system vented, and thus advise the engineer that one of the stop-cocks of the system 35 has been tampered with.

In the accompanying drawings, wherein my invention will be found fully illustrated, Figure 1 is a view, shown partly in side elevation and partly in section, of my improved stop-cock. Fig. 2 is a view showing partly in elevation and partly in section the plug or valve of said stop-cock. Fig. 3 shows the key, and Fig. 4 is a view of the cover-plate for the locking mechanism.

45 The stop-cock *a* has the port *b* extending therethrough, the conical plug or valve *c*, provided with the port *d*, and a handle *e*, arranged to abut against a stop *f* on the body of the stop-cock when the valve is open, a plug *g*, 50 screwed into the conical bore *h* of the stop-cock which receives the valve *c*, and the spiral spring *i*, interposed between the plug and the valve, all as in the usual construction of devices of this nature.

The body of the stop-cock is formed with 55 an integral shell *j* in an opening *k*, in the wall of which adjoining the valve *c* and in a recess *l* opposed to said opening and formed in the opposite wall of said shell is arranged to slide a bolt *m*, having a shoulder *n*, between which 60 and the wall of the shell in which the recess *l* is formed is interposed a spiral spring *o*, coiled about the bolt. The recess *l* is squared in cross-section, and the bolt having a similar cross-section and being fitted thereto is thus 65 prevented from rotation. In the valve *c* is a recess *p*, which when alined with the opening *k* is adapted to receive the end of the bolt *m*. The recess is so arranged that the bolt *m* will be received by the recess to lock the valve 70 when the latter's port *d* opens up communication through the stop-cock.

q is the key for operating the bolt *m*; *r*, a centering-spindle for the key arranged in the chamber or shell *j*; *s*, an arc-shaped guard 75 arranged concentrically with reference to the spindle *r* and formed to fit the bit of the key, and *t* a notch formed in the bolt to receive the bit of the key and affording a shoulder *u*, whereupon the bit may engage to shoot the 80 bolt.

v is a cover-plate for the shell *j*.

It will be understood that inasmuch as the keys will be carried only by authorized persons the valve *c* cannot be operated unless a 85 key is employed to shoot the bolt; but in order to prevent the valve being under any circumstances moved by any one without the knowledge of the engineer the valve *c* is provided with a port *w*, which communicates, on 90 the one hand, with a port *x*, leading to the main port *b*, and, on the other hand, with the atmosphere whenever ports *w* and *x* coincide—*i. e.*, when the valve is in the fully-closed position. Thus constructed, if any 95 stop-cock in the system were closed the engineer would be at once advised thereof, because the air-escape provided by way of the ports *x* and *w* would set the brakes on the part of the train forward of the stop-cock thus manipulated and so advise the engineer. The port *w* has its upper end turned downwardly, as seen in Fig. 2, and since it opens through a surface of the valve-handle *e*, which overhangs and is close to the top of the shell *j*, its discharge 100 end is more or less hidden and inaccessible and the accumulation of dirt, &c., which clog it up, is prevented.

Having thus fully described my invention, what I claim as new, and desire to secure by Letters Patent, is—

1. In an air-brake system, a stop-cock comprising the body portion formed with an integral shell, the rotating valve having a radial bolt-receiving recess, and a spring-actuated key-operative bolt arranged in said shell in operative position to engage in said recess, substantially as described.
2. In an air-brake system, a stop-cock comprising the body portion formed with an integral shell, the rotating valve having a radial bolt-receiving recess, a key-operative bolt arranged in opposite walls of said shell in operative position to engage said recess and having, within the shell, a shoulder, and a spring interposed between one wall of said shell and the shoulder and coiled about said bolt.

3. In an air-brake system, a stop-cock comprising the body portion and the valve having a part thereof overhanging and disposed close to said body portion; said body portion having a port leading from the main port of the stop-cock to the valve-bore and said valve having a port adapted to register with said first-named port and leading to the atmosphere through the surface of said overhanging part which is next adjacent to the body portion, substantially as described.

In testimony that I claim the foregoing I have hereunto set my hand this 17th day of March, 1906.

SAMUEL H. DUNNING.
